US0D1095042S

(12) **United States Design Patent** (10) Patent No.: **US D1,095,042 S**
(45) Date of Patent: ** Sep. 30, 2025

(54) **TOOTHBRUSH HANDLE**

- (71) Applicant: **The Gillette Company LLC**, Boston, MA (US)
- (72) Inventors: **Christine Hallein**, Frankfurt (DE); **Uwe Jungnickel**, Königstein (DE); **Dominik Langhammer**, Frankfurt (DE); **Angelika Beruda**, Schwalbach (DE); **Frank Roland Glemroth**, Schwalbach (DE); **Andre Lerch**, Frankfurt (DE); **Kathrin Lange**, Frankfurt (DE); **Armin Tschol**, Frankfurt am Main (DE)
- (73) Assignee: **The Gillette Company LLC**, Boston, MA (US)
- (**) Term: **15 Years**
- (21) Appl. No.: **29/889,761**
- (22) Filed: **Apr. 17, 2023**

Related U.S. Application Data

- (62) Division of application No. 29/782,323, filed on May 6, 2021, now Pat. No. Des. 994,341.

(30) **Foreign Application Priority Data**

CLAIM

The ornamental design for toothbrush handle, as shown and described.

DESCRIPTION

FIG. 1 is a perspective view of a toothbrush handle; FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom view thereof.

The broken lines used in the drawings are for the purpose of depicting portions of the toothbrush handle, and form no part of the claimed design.

1 Claim, 3 Drawing Sheets
